CENTRIFUGAL PUMP

John William Summers, Kelowna, British Columbia, Canada

Application October 1, 1943, Serial No. 504,627

7 Claims. (Cl. 103—104)

My invention relates to pumps, and has among its objects and advantages the provision of an improved centrifugal pump.

In the accompanying drawings:

Figure 1 is an elevational view of the pump.

Figure 2 is a top view.

Figure 3 is an elevational view illustrating the pump from a position inside a pressure tank.

Figure 4 is an enlarged sectional view along the line 4—4 of Figure 2.

Figure 5 is a sectional view along the line 5—5 of Figure 4, and

Figure 6 is a reduced sectional view taken along the line 6—6 of Figure 4.

In the embodiment of the invention selected for illustration, I make use of a pump housing 10 comprising identical sections 12 provided with flanges 14 coacting with bolts 16 to secure the sections into a unitary structure. Both sections are provided with flanges 18 bolted at 20 to a flange 22 on a neck 24 opening into a storage or pressure tank 26.

In Figure 4, the sections 12 include outwardly curved or dished end walls 28 and curved side walls 30, the latter defining a single side wall. Figure 2 illustrates the side walls 30 as extending throughout a curvature of slightly more than 180 degrees. The flanges 18 are slightly curved when viewed according to Figure 2 in conformity of the curvature of the surrounding area of the tank 26. Each section 12 also includes an inner wall 32 reversely dished with respect to the end wall 28 of that section. The inner walls 32 are of the same contours as the end walls 28 when viewed according to Figure 6, since the walls 32 connect with side walls 34 constituting continuations of the flanges 18. The walls 28, 30, 32 and 34 may be welded into a unitary structure, but the sections 12 are detachably connected by reason of the flanges 14 and the bolts 16.

An impeller 36 is mounted in an impeller housing 38 located between the inner walls 32. This impeller comprises two identical sections 40 separated by a thin metal wall 42. Figure 5 illustrates a face view of one of the sections 40, the two being identical. Long blades or vanes 44 are arranged radially of the axis of the impeller and connect with the impeller hub 46. These blades extend to the periphery of the plate 42, and the blades are reversely curved at 48 with respect to the direction of rotation of the impeller which is clockwise when viewing Figure 5. Spaced between the vanes 44 are shorter vanes 50 curved in conformity with the vanes 44 and extending inwardly from the periphery of the impeller to a

short distance from the hub 46. Progressively shorter vanes 52 and 54 are arranged between the vanes 50 and 44.

In Figure 4, the two hubs 46 are mounted on a shaft 56 rotatably supported in thrust bearings 58 carried by brackets 60 bolted to the respective end walls 28. The shaft 56 is positioned vertically and extends through packing glands 62 carried by the end walls 28.

10 A collar 64 is fixed to the shaft 56 and abuts one hub 46. A sleeve 66 is mounted on the shaft and engages the other hub 46. The two hubs and the plate 42 are clamped into a unitary structure by a nut 68 threaded on the shaft 56 and abutting the sleeve 66.

The impeller housing 38 comprises two walls 70 of identical construction and of dished formation to closely house the impeller sections 40, the blades of which are tapered in accordance with Figure 4. Both walls 70 have inturned peripheral margins 72 spaced to constitute an outlet extending circumferentially about the impeller throughout 360 degrees.

Between the flat areas 74 of the walls 32 and 25 the walls 70 are interposed sealing means 76, and all these parts are secured into a unitary structure by bolts 78. All the walls 32 and 70 are provided with inlet openings 80 arranged concentrically of the shaft 56. The two inlet openings 20 are of equal size. To each wall 28 is connected two water inlet conduits 82, although one larger conduit for each inlet chamber 84 operates satisfactorily.

35 A motor 86 drives the shaft 56 and is mounted on a bracket 88 attached to the tank 26 and additionally supported by a brace 90 attached to the lowermost section 12.

The impeller housing 38 extends partly through the neck 24, and the outlet chamber 92 diverges 40 radially of the impeller housing 38 and communicates with the neck 24.

A pump in accordance with my invention is highly efficient in terms of capacity by reason of the fact that the impeller housing includes an 45 outlet extending circumferentially about the impeller throughout 360 degrees. The impeller is fed from both sides and the vane arrangement functions with a high capacity. The impeller housing may be accurately adjusted to the impeller through addition or removal of shims or sealing means between walls 32 and 70. The parts are of simple construction and are so designed and assembled as to provide a sturdy pump of relatively few parts.

55 The plate 42 is provided with a plurality of

small openings 84 constituting air vents. An air releasing valve 86 is provided in the top wall 28 so that any air trapped in the pump may be released to the atmosphere.

Without further elaboration, the foregoing will so fully explain my invention, that others may, by applying current knowledge, readily adapt the same for use under various conditions of service.

I claim:

1. The combination with a storage tank having an opening therein and a neck surrounding the opening, a pump housing mounted on the neck and having upper, lower and side walls, inner walls in the housing forming upper and lower inlet compartments, a centrifugal pump comprising an impeller, and a chamber between the inlet compartments for said impeller, said chamber being provided with an outlet extending circumferentially of the impeller throughout 360 degrees and communicating with the opening in the storage tank.

2. The combination with a storage tank having an opening therein and a neck surrounding the opening, a pump housing mounted on the neck and having upper, lower and side walls, inner walls in the housing forming upper and lower inlet compartments, a centrifugal pump comprising an impeller, a chamber between the inlet compartments for said impeller, said chamber being provided with an outlet extending circumferentially of the impeller throughout 360 degrees and communicating with the opening in the storage tank, and said inlet chambers communicating with said housing on opposite sides thereof and coaxially of the axis of rotation of the impeller.

3. The combination with a storage tank having an opening therein and a neck surrounding the opening, a pump housing mounted on the neck and having upper, lower and side walls, inner walls in the housing forming upper and lower inlet compartments, a centrifugal pump comprising an impeller, a chamber between the inlet compartments for said impeller, said chamber being provided with an outlet extending circumferentially of the impeller throughout 360 de-

grees and communicating with the opening in the storage tank, said inlet chambers communicating with said housing on opposite sides thereof and coaxially of the axis of rotation of the impeller, and inlets communicating with said chambers.

4. The invention described in claim 1 wherein said housing comprises two sections, means for adjusting said sections relatively to the impeller, said impeller being sectional, and a dividing wall between the sections of the impeller.

5. The invention described in claim 1 wherein said inlet chambers are located at opposite sides of said impeller housing, said housing comprising two sections respectively connected with said inlet chambers, said impeller comprising two sections, and a dividing means between the two sections of the impeller.

6. The combination with a storage tank having an opening therein, a neck surrounding the opening, a pump housing having a wall adjacent to the tank and secured to the neck, and upper and lower walls and side walls connected with each other and with the first wall, inner walls in the housing spaced from the upper and lower walls to divide said housing with upper and lower inlet compartments having inlet openings, an impeller, an impeller casing mounted between the inner walls and having spaced walls giving an outlet completely about the periphery of the impeller and said impeller and casing partly extending through the neck and into the tank, and an outlet chamber extending about the impeller casing and leading into the tank through the neck and opening therein.

7. The invention as defined in claim 6, wherein the respective inner and outer walls of the housing are oppositely curved in cross-section, and wherein the impeller casing walls are curved in cross-section opposite the direction of curvature of the inner walls, and wherein the outlet about the impeller extends throughout 360 degrees, a portion of which serves directly into the tank and the remainder into the outlet chamber.
